UNITED STATES PATENT OFFICE.

JAMES J. FAIRBANKS, OF GARDNER, MASSACHUSETTS, ASSIGNOR, BY DIRECT AND MESNE ASSIGNMENTS, TO THE U. S. TOY & NOVELTIES MFG. CO., OF TEMPLETON, MASSACHUSETTS, A CORPORATION OF MASSACHUSETTS.

DESIGN FOR A TOY FERRIS WHEEL.

54,202.

Specification for Design.

Patented Nov. 18, 1919.

Application filed August 6, 1919. Serial No. 315,764. Term of patent 14 years.

To all whom it may concern:

Be it known that I, JAMES J. FAIRBANKS, a citizen of the United States of America, residing at Gardner, in the county of Worcester and State of Massachusetts, have invented a new, original, and ornamental Design for a Toy Ferris Wheel, of which the following is a specification, reference

being had to the accompanying drawing, forming part thereof.

The figure is a view in perspective of a toy Ferris wheel, showing my new design.

I claim:—

The ornamental design for a toy Ferris wheel, as shown.

JAMES J. FAIRBANKS.
